REVERSIBLE TOY VEHICLE

Samuel I. Berger, Newark, N. J.

Application January 12, 1950, Serial No. 138,173

13 Claims. (Cl. 46—212)

1

This invention relates to mechanical toys and more particularly to a toy vehicle.

It is among the objects of the invention to provide a toy vehicle that has but few parts, none of which are delicate or likely to become out of order and which are relatively simple and inexpensive to construct and assemble, which vehicle is capable of traveling in a definite direction and can change its course upon contact of any portion of its body with an obstacle, to clear the latter, without the need for clutches or any complicated mechanism.

According to the invention these objects are accomplished by the arrangement and combination of elements hereinafter described and particularly recited in the claims.

In the accompanying drawing in which is shown one of various possible embodiments of the several features of the invention,

Fig. 1 is a longitudinal sectional view of the vehicle taken along line 1—1 of Fig. 2,

Fig. 2 is a bottom plan view of the vehicle,

Fig. 3 is a fragmentary view similar to Fig. 2 showing the truck turned 90 degrees,

Fig. 4 is a transverse sectional view taken along line 4—4 of Fig. 2, and

Fig. 5 is a perspective view of the stop plate.

Referring now to the drawings, in the embodiment herein shown to illustrate my invention, the toy vehicle desirably comprises an elongated substantially rectangular frame 11, preferably of sheet metal and desirably having a pair of transversely aligned ears 12 near one end thereof, depending from said frame and preferably integral therewith, said ears mounting an axle 13 on which a pair of wheels 14 is rotatably mounted.

A truck 15, desirably a substantially U-shaped member, is rotatably mounted beneath said frame 11, near the other end thereof, preferably on the vertical drive shaft 16 of a motor M, with said shaft 16 extending through an opening 17 in the cross piece 18 of the truck and perpendicular to said cross piece.

The motor M, which is desirably of the conventional spring wound type is mounted on the upper surface of the frame as by means of tines 19, desirably formed integral with casing 21 of the motor and extending through suitable openings in the frame. A cover 22 which may serve as the body of the vehicle is desirably affixed to the frame over the motor M to conceal the latter.

The truck 15 carries a pair of spaced parallel wheels 23 and 24, desirably mounted on an axle 25 positioned at right angles to drive shaft 16 and extending through bearing openings 26 in the depending legs 27 of the truck.

2

One of said wheels, i. e. wheel 23, is idly mounted on said axle and the other of said wheels, i. e. wheel 24, is rigidly mounted on said axle to be driven by the latter through a transmission from the main drive shaft which includes a crown gear 28 and a meshed pinion 29 affixed on the drive shaft 16 and the axle 25 respectively.

Thus, as only one of the wheels is driven, the tendency will be for the truck 15 to rotate about shaft 16 when the vehicle is placed on a surface.

Means are provided to prevent vertical displacement of said truck 15 on said drive shaft 16 which would cause the pinion 29 to be disengaged from the crown gear 28. Although any suitable means could be used for this purpose, in the embodiment herein shown, a substantially U-shaped yoke 32 is provided having an opening 33 through the cross piece 34 thereof through which said drive shaft 16 extends. The upper ends of the upstanding legs of the yoke 32 are affixed to the cross piece 18 of the truck 15 as by means of the tines 36, securely to retain the yoke in place with the cross piece 34 thereof adjacent the hub 37 of crown gear 28.

The construction thus far described is not necessarily claimed herein as it is conventional.

According to the present invention, a pair of complementary elements are mounted on the frame 11 and the truck 15 respectively to engage each other, to restrain rotation of said truck 15 about drive shaft 16 to cause the vehicle to travel in a definite direction. One of said elements is movable by its mount in a circular path with respect to the other of said elements, and said elements are constructed so that the movable element will move across the other of said elements for release thereof when said vehicle hits an obstacle, to permit rotation of said truck 15 to change the direction of travel of the vehicle.

Although the complementary elements, one of which is displaceable on its mount and the other of which is fixed, may be of any suitable type, and the displaceable element may be mounted on the truck 15 or on the frame 11, in the embodiment herein shown to illustrate the invention, the displaceable element is mounted on the truck and movable therewith, and desirably comprises a ball 41 positioned in an opening 42 in the cross piece of the truck, and the other element desirably comprises a stop 43 fixed with respect to the frame 11 and in the circular path of movement of said ball 41 on its mount.

The ball 41 which is desirably of smaller diameter than opening 42 is resiliently retained therein as by means of a leaf spring 44 with diametrically opposed portions of the periphery of the

ball protruding through said opening. Leaf spring 44 is rigidly affixed at one end to cross piece 18 as by means of an eyelet 45 extending through opening 17 and serving as a bearing for the drive shaft 16. The free end of the leaf spring 44 desirably has a seat therein, preferably an opening 46 of smaller diameter than said ball, to prevent lateral displacement thereof.

Preferably two stops 43 are provided, desirably protuberances in the circular path of movement of said ball and positioned approximately 180 degrees apart. Thus, when the wheels 23, 24 turn in a clockwise direction as shown in Fig. 1, the truck 15 will tend to turn in a counterclockwise direction as shown in Fig. 2, and when the ball 41 abuts against either of the stops 43, the axle of the wheels 23, 24 will be transversely aligned with the frame 11, to cause the vehicle to move forwardly or rearwardly as the case may be depending upon which of the stops 43 is engaged by the ball 41, the vehicle moving in the direction of the arrow when the truck 15 is in the position shown in Fig. 2.

Although the stops 43 could be formed in the frame 11 itself and the portion of the periphery of said ball 41 extending through said opening 42 adjacent the frame 11, could ride on the undersurface of the latter, it is preferred to provide a stop plate 48 in the form of a disc having an annular groove or track 49 for the ball pressed therein near the periphery thereof and having the stops 43 extending transversely across said annular groove 49.

As shown in Fig. 4, the stop plate desirably is affixed by tines 51 to the undersurface of the frame 11 and has a hub 52 of relatively large diameter through which the drive shaft 16 extends, the hub serving as a wide bearing surface for the cross piece 18 of the truck 15 to prevent tilting of the latter.

With the construction thus described, when the vehicle is in motion the tension of the leaf spring 44 will retain the ball 41 in said annular groove 49, abutting against one of said stops 43 as shown in Fig. 4.

Thus, although the truck 15 has a tendency to rotate about drive shaft 16, such rotation will be restrained by the coaction of ball 41 and stop 43 and the vehicle will travel along substantially a straight line in a definite forwardly or rearwardly direction.

When an obstacle is in the path of the vehicle, as the latter can no longer move forward, the drive imparted by driven wheel 24 will tend to rotate the truck about drive shaft 16 and the sudden force applied by ball 41 against the stop 43 with which it is in contact will cause the ball to ride over said stop.

The truck 15 will thereupon be free to rotate, and as it rotates, the direction of travel of the vehicle will continuously change and the vehicle will tend to move in a circular path until the ball 41 abuts against the other stop 43. When this occurs the rotation of the truck 15 will again be restrained and the vehicle will move along substantially a straight line in a direction opposite to its original path of travel until another obstacle is struck, at which time the procedure above described will be repeated.

As many changes could be made in the above construction, and many apparently widely different embodiments of this invention could be made without departing from the scope of the claims, it is intended that all matter contained in the

above description or shown in the accompanying drawings shall be interpreted as illustrative and not in a limiting sense.

Having thus described my invention, what I claim as new and desire to secure by Letters Patent of the United States is:

1. A toy vehicle comprising a wheeled frame, a truck beneath said frame having a pair of spaced parallel wheels, one of said wheels being idly mounted, drive means positively to rotate the other of said wheels, means rotatably mounting said truck on said frame on an axis perpendicular to the frame and to the axes of said wheels, a pair of complementary elements mounted on said frame and said truck respectively, to engage each other to restrain rotation of said truck thereby to cause said vehicle to travel in a definite direction, means mounting one of said elements for vertical movement away from the other of said elements, said vertically movable element being movable by its mount in a circular path with respect to the other of said elements, whereby when said vehicle hits an obstacle, said movable element will move across the other of said elements for release thereof thereby permitting rotation of said truck to change the direction of travel of said vehicle.

2. A toy vehicle comprising a wheeled frame, a truck beneath said frame having a pair of spaced parallel wheels, one of said wheels being idly mounted, drive means positively to rotate the other of said wheels, means rotatably mounting said truck on said frame on an axis perpendicular to the frame and to the axes of said wheels, a pair of complementary elements mounted on said frame and said truck respectively to engage each other to restrain rotation of said truck thereby to cause said vehicle to travel in a definite direction, means mounting the element mounted on said truck for vertical movement away from the element mounted on said truck being movable in a circular path with respect to the element mounted on said frame, whereby when said vehicle hits an obstacle, said movable element will move across the other of said elements for release thereof thereby permitting rotation of said truck to change the direction of travel of said vehicle.

3. A toy vehicle comprising a wheeled frame, a truck beneath said frame having a pair of spaced parallel wheels, one of said wheels being idly mounted, drive means positively to rotate the other of said wheels, means rotatably mounting said truck on said frame on an axis perpendicular to the frame and to the axes of said wheels, coacting means on said frame and said truck respectively to restrain the rotation of the latter, said means including a stop and a displaceable member releasably to engage said stop to cause said vehicle to travel in a definite direction, means mounting the displaceable member for vertical movement away from the stop, said drive means being adapted to rotate said truck on its axis when said vehicle hits an obstacle to effect relative movement between said stop and said displaceable member for disengagement thereof to change the direction of travel of said vehicle.

4. A toy vehicle comprising a wheeled frame, a truck beneath said frame having a pair of spaced parallel wheels, one of said wheels being idly mounted, drive means positively to rotate the other of said wheels, means rotatably mounting said truck on said frame on an axis perpendicular to the frame and to the axes of said

wheels, coating means on said frame and said truck to restrain the rotation of the latter, said means including a pair of spaced stops and a displaceable member releasably and successively to engage said stops to cause said vehicle to travel in a definite direction, means mounting the displaceable member for vertical movement away from the stops, said drive means being adapted to rotate said truck on its axis when said vehicle hits an obstacle to effect relative movement between said engaged stops and said displaceable member for disengagement of said engaged stop and rotation of said truck until engagement of the other stop and said displaceable member to change the direction of travel of said vehicle.

5. The combination set forth in claim 4 in which said spaced stops are so positioned with respect to said frame and to the axes of said wheels on said truck that when either of said stops is engaged by said displaceable member, the axes of said wheels will extend transversely of said frame.

6. A toy vehicle comprising a wheeled frame, a truck beneath said frame having a pair of spaced parallel wheels, one of said wheels being idly mounted, drive means positively to rotate the other of said wheels, means rotatably mounting said truck on said frame on an axis perpendicular to the frame and to the axes of said wheels, a displaceable member mounted on said truck and a stop mounted on said frame in the path of movement of said displaceable member, means mounting said displaceable member for vertical movement away from the stop, whereby when said stop is engaged by said displaceable member the rotation of said truck will be restrained to cause said vehicle to travel in a definite direction, said displaceable member being movable across said stop for release thereof when said vehicle hits an obstacle, thereby permitting rotation of said truck to change the direction of travel of said vehicle.

7. A toy vehicle comprising a wheeled frame, a truck beneath said frame having a pair of spaced parallel wheels, one of said wheels being idly mounted, drive means positively to rotate the other of said wheels, means rotatably mounting said truck on said frame on an axis perpendicular to the frame and to the axes of said wheels, a stop conformation on said frame and a resiliently urged member mounted on said truck and movable in a circular path to abut against said stop to restrain the rotation of said truck thereby to cause the vehicle to travel in a definite direction, means mounting said displaceable member for vertical movement away from the stop, said resiliently urged member being movable across said stop for release of the latter, thereby permitting rotation of said truck when

said vehicle hits an obstacle to change the direction of travel of said vehicle.

8. The combination set forth in claim 7 in which said truck has a cross piece extending parallel to the axes of said wheels and said resiliently urged member is mounted on said cross piece.

9. A toy vehicle comprising a wheeled frame, a truck beneath said frame having a pair of spaced parallel wheels, one of said wheels being idly mounted, drive means positively to rotate the other of said wheels, said truck having a cross piece extending parallel to the axes of said wheels, said cross piece having an opening therethrough, means associated with said cross piece rotatably to mount the truck on said frame on an axis perpendicular to the frame and to the axes of said wheels, a ball positioned in said opening in the cross piece of the truck and movable in a circular path by the truck, a leaf spring affixed to said cross piece and retaining the ball in said opening with a portion of its periphery protruding therefrom, a stop conformation rigidly mounted on said frame and in the circular path of movement of said ball to restrain the rotation of said truck to cause the vehicle to travel in a definite direction, said ball riding over said stop for release of the latter, thereby permitting rotation of said truck when said vehicle hits an obstacle to change the direction of travel of said vehicle.

10. The combination set forth in claim 9 in which an annular groove is provided on said frame to serve as a track for said ball and said stop extends radially across said groove.

11. The combination set forth in claim 9 in which a disc is rigidly mounted on said frame and has an annular groove therein to serve as a track for said ball and a plurality of stop conformations are provided extending radially across said groove.

12. The combination set forth in claim 11 in which said stop conformations are approximately 180 degrees apart.

13. The combination set forth in claim 11 in which said disc has a relatively wide hub to serve as a bearing surface for the cross piece of said truck to prevent tilting of the latter.
